[57] CLAIM

The ornamental design for a ruler, as shown and described.

DESCRIPTION

FIG. 1 is a top plan view of the ruler;

FIG. 2 is a bottom plan view of FIG. 1;

FIG. 3 is a top perspective view of FIG. 1;

FIG. 4 is an end view of FIG. 1;

FIG. 5 is a front elevation of FIG. 1;

FIG. 6 is an end cross-section on FIG. 4; and,

FIG. 7 is a perspective view of FIG. 1.

In FIGS. 1-3 and 5 of the drawing, portions have been omitted for ease of illustration.

The broken line showing of scale markings and indicia is for illustrative purposes only and forms no part of the claimed design.
